(57) **CLAIM**

We claim the ornamental design for a bracket assembly, as shown and described.

DESCRIPTION

FIG. 1 is a top perspective view of one embodiment of a bracket assembly of the present invention;

FIG. 2 is a front elevational view of the bracket assembly of FIG. 1;

FIG. 3 is a side elevational view of the bracket assembly of FIG. 1;

FIG. 4 is a top plan view of the bracket assembly of FIG. 1; and,

FIG. 5 is a bottom plan view of the bracket assembly of FIG. 1.

The broken lines represent portions of the design that form no part of the claim.
